COLUMBIA PLANOGRAPH CO., WASHINGTON, D. C.

UNITED STATES PATENT OFFICE.

JACOB B. ROSENSTEIN, OF CLEVELAND, OHIO.

CLOTH-PILEING MACHINE.

1,075,729.

Specification of Letters Patent.

Patented Oct. 14, 1913.

Application filed February 3, 1911. Serial No. 606,347.

To all whom it may concern:

Be it known that I, JACOB B. ROSENSTEIN, a citizen of the United States, and resident of Cleveland, in the county of Cuyahoga and State of Ohio, have invented certain new and useful Improvements in Cloth Piling Machines, of which I hereby declare the following to be a full, clear, and exact description, such as will enable others skilled in the art to which it appertains to make and use the same.

The objects of the invention are to provide automatically operating mechanism for folding cloth into required lengths of material so as to prepare it for manufacturing purposes and particularly for folding the cloth into lengths preparatory to the cutting of patterns for making it up into wearing apparel; and the invention comprises mechanism adapted to reciprocate upon a table and to carry the cloth backward and forward thereon through a predetermined distance as it comes from the roll, so as to lay it in folds upon the table, and also includes automatically operating devices for holding the cloth at each limit of movement of the reciprocating device so as to form the folds with regularity and precision of exactly equal length.

The invention further comprises automatically acting devices for operating the cloth holding devices, to release them from the fold at the proper moment before the return of the reciprocating carrier and thereafter to place them upon the cloth so as to form another fold.

The invention also includes the various details of construction and combination and arrangement of parts as hereinafter described, shown in the accompanying drawings and specifically pointed out in the claims.

In the accompanying drawings Figure 1 is a plan view of the device showing one set of fold holders in use and the carrier conveying the cloth to the other set; Fig. 2 is a side elevation of the same; Fig. 3 is a transverse section of the machine and table; Fig. 4 is a plan view of one of the fold holders and operating arm and cams therefor; Fig. 5 is a side elevation of the same; Fig. 6 is an enlarged transverse section of friction rollers upon the carrier and tension device therefor; Fig. 7 is a plan view of one end of the same; Fig. 8 is a detail view of one of the holding fingers;

Fig. 9 is a transverse section of the ball bearing for one of the holding fingers; Fig. 10 is a transverse section of the guide rails and of the adjustable support for the finger operating arm; Fig. 11 is a transverse section showing a frame for the machine separate from the table.

In these views, 1 is the table, 2, 2, are guide rails elevated above the table on each side and upon these rails are mounted the carriers 3, 3 upon rollers 4, 4, and the carriers are connected by means of the transverse rod 5 the central portion of which may be provided with a roller 5' over which the cloth 6 is passed before folding. Before it passes over the rod 5 the cloth passes over the rollers 7, 7 and underneath the pressure roller 8, mounted on the brackets 8', 8', and is thereby placed under tension so that the cloth will be smoothly laid. 9 is a guide for the roll of cloth. The amount of tension can be varied at will by means of the spring pressed pin P and screw collars Q, Q inserted in swinging bearings R, 80 R which permit of removing the upper roll.

The carriers 3, 3, are reciprocated upon the rails 2, 2, by means of the cords 10 which are attached to arms 18 and pass over the pulleys 10', 10² one set at each end of the machine. The pulleys 10', 10² are secured upon shafts 11' and 11 respectively which are alternately rotated in opposite directions in any desired manner. As shown the shaft 11 is provided with loose pulleys 90 12 and 13 over one of which is a crossed belt 14 so that the pulleys revolve in opposite directions. The pulleys 10' 10² are enabled to rotate alternately in opposite directions to give the carrier a reciprocating movement, by means of a reversing device whereby the shaft 11 is alternately connected with one or the other of the loose pulleys 12 and 13. This reversing device 95 may be constructed as follows: 15 is a shifting or reversing rod mounted in bearings 16, 16 at one side of the machine. The rod is provided with sliding sleeves 17, 17 adapted to be struck by the arm 18 which depends from the carrier. Springs 20, 20 take the shock of the impact and it is received upon fixed collars 21, 21. The movement of the shifting rod 15 operates a shifting lever 22, link 23 and rock bell crank 24 which moves a double clutch 25 to 110 engage the pulleys 12 and 13 alternately. The fixed collars 21, 21 can be adjusted upon

the shifting rod to reverse the movements of the carriers according to the length of the folds desired.

24', 24' are fingers adapted to be laid on the cloth on each edge and over which the cloth is folded as the carrier moves forward or backward over the table. Each finger 24' is mounted upon a rod 25 having a ball bearing 26 in a swinging arm 27 which is pivoted at 28 upon a support 29 which in turn is longitudinally adjustable upon the table upon guide rails 30 by means of a clamping screw 31 and nut 32 as shown in Fig. 9. The outer portion 33 of the arm to which the finger is attached is pivoted in the other portion at 34 to permit vertical movement thereof so that the finger can be raised to remove it from the cloth and again lowered to place it in position to make another fold. The arm 27 is raised as it swings by means of a cam 35 on the support 29, and the finger is kept in alignment at right angles to the edge of the table by means of slotted front guide bars 36 and inclined rear guide bars 37 between which it operates. The forward portion 38 of the finger is hinged at 39 and is normally held in a horizontal position by means of a spring 40 but the hinge permits of its being withdrawn from a fold by bending as it is raised up by the arm 27 and cam 35. The inclination of the rear guide bars is such as to permit the arm 27 to rise upward and also move rearwardly so as to withdraw the finger from the edge of the cloth; while descending however it is desirable that the finger should fall vertically upon the cloth since if it were pushed gradually forward it would be likely to move the cloth with it. The outer ends of the fingers 24' are made adjustable at 60 so that their length can be varied to suit the width of the cloth. To prevent this action a plate 41 is pivoted at 42 in the path of a pin 43 which is attached to the swinging arm and an opening 44 is left in this plate at one end. The outer ends of the fingers 24, 24 are made detachable at 60 so that their length can be varied to suit the width of the cloth. The pin 43 when rising will raise this plate and pass beyond it but before falling will traverse the plate until it reaches the opening 44 and will then fall vertically through it and the finger will follow the same course and fall vertically on the goods.

The swinging arms 27 are operated by means of cams on the carriers so as to operate coincidentally with the movement thereof. They are four in number and those at one end of the machine are operated alternately with those at the other end of the machine, as the carrier reciprocates on its guides.

As shown in Fig. 1 the pair of fingers 24' 24' at the left of the figure are inserted

in a fold in the cloth and the carrier rod 5 has passed beyond the fold and is at the point of return and the arm 18 on the carrier is engaging the shifting rod. At the right of the figure the pair of fingers 24', 24' are shown withdrawn from the cloth. The cams by means of which this action of the fingers and swinging arms is obtained are preferably arranged as follows: Each arm is provided with two reversely inclined cams 50 and 51 and the finger carrying extremities of one pair of arms extend toward the extremities of the other pair so that the cams on the carrier will have equal effect on the movements of all the arms. 80 Each carrier is provided with two opposite and reversely inclined cam surfaces 52 and 53 adapted to engage the cams 50, 50 in turn on each pair of arms and with the double cam 54 at a lower level adapted to 85 engage the cams 51, 51 alternately on each pair of arms. These cams on the carrier act to swing the arms alternately in opposite directions and the cams on the arm lift so as to pass the cams on the carrier not intended to operate them, and to engage the ones which are intended to operate them, so that one cam will not interfere with the action of the other. 90

The action is as follows: As the carrier 3 moves forward the cam 50 on each side will strike and rise above the cam 52 and the cam 54 will strike the cam 51 and throw the arm 27 outward until the finger is released from the cloth. As soon as the carrier 3 begins to return the cam 53 will strike against the cam 50 and throw the arm inward and it will rise on the incline 36 and fall through the opening 44 upon the cloth. The cam 51 will then rise over the cam 54 105 and no further action will be taken until the return stroke of the carrier. In this manner the cloth is alternately held and released as the carrier reciprocates. 110

In Fig. 11 is shown a frame for this machine so arranged as to be attachable to any table.

Having described the invention what I claim as new and desire to secure by Letters Patent is—

1. In a cloth piling machine, a table, a cloth carrying device reciprocable thereon, means in said carrier for placing said cloth under tension, a pair of fingers at each end of the machine, one pair adapted to engage the cloth alternately with the other pair, a combined hinged and swinging arm to which each finger in each pair is secured, guides arranged to hold each finger in a transverse position relatively to the edge 125 of the cloth, one of said guides inclined to permit the finger to be withdrawn laterally therefrom, a cam adapted to raise each swinging arm and a device adapted to cause each finger to fall vertically by gravity, and 130

engaging devices upon said carriers and swinging arms, whereby said carriers are caused to operate each pair of said arms alternately, and means for reciprocating 5 said carrier.

2. In a cloth piling machine, the combination of a table, a reciprocating carrier thereover, pivoted arms adjacent to the path thereof, cams on each side of the table and 10 at each end thereof, the said cams arranged on the carrier and arms and adapted to engage and swing the arms in opposite directions as said carrier reciprocates, a stationary cam adapted to raise one end of 15 each arm, a horizontal finger pivotally secured to each arm, guides in which said fingers move, one set of said guides being inclined to permit of laterally swinging said arms, and a swinging plate at the top of 20 each inclined guide, said plate provided with an opening, adapted to permit the finger in said guide to fall vertically by gravity.

3. In a cloth piling machine, in combination, a table, a pair of horizontally swinging arms at one end of the table, one arm at each side thereof, a similar pair of arms at the other end of the table, a carrier on 25 each side of the table reciprocable on said machine, arm operating cams on said carriers and corresponding cams on said arms,

35 said cams on said arms arranged on both sides of the pivotal point thereof, a cam for raising one end of each arm, a horizontal finger pivotally secured to the outer end 40 of each arm, and means raised by said finger for temporarily retaining the same in an elevated position until the end of the arm has swung inwardly, the said retaining means permitting the finger to fall vertically.

4. In a piling device for a cloth folding machine, in combination with a swinging arm, operating cams thereon arranged one 45 at each side of the pivotal point, a hinged outer end to the arm, a horizontal finger having a hinged outer end and supporting spring therefor, means for pivotally securing said finger in the outer end of said arm, a vertical front guide for the finger, an inclined rear guide therefor, and a hinged plate provided with an opening, said plate 50 raised by said arm as it rises, said opening in said plate permitting the said arm to fall by gravity as the arm moves inwardly.

55 In testimony whereof, I hereunto set my hand this 1st day of February 1911.

JACOB B. ROSENSTEIN.
